UNITED STATES PATENT OFFICE.

ISRAEL MARION SWANK AND ALFRED C. COSNER, OF NORTH MANCHESTER, INDIANA, ASSIGNORS OF ONE-THIRD TO JONAS GROSSNICKLE, OF SAME PLACE.

BATHING APPARATUS.

SPECIFICATION forming part of Letters Patent No. 427,377, dated May 6, 1890.

Application filed January 6, 1890. Serial No. 336,007. (No model.)

To all whom it may concern:

Be it known that we, ISRAEL MARION SWANK and ALFRED C. COSNER, citizens of the United States, residing at North Manchester, in the county of Wabash, State of Indiana, have invented certain new and useful Improvements in Bathing Apparatus, of which the following is a specification, reference being had therein to the accompanying drawings.

Our invention relates to bath-tubs which may be folded into a cabinet when not in use or removed from one apartment or building to another; and the objects of our improvement are to produce a bathing apparatus having the desired means for heating water or for producing steam, either to heat the water in the bath-tub, or for producing a steam or sweat bath in said tub, or for cooking substances, and which apparatus shall be of good appearance when used either as a lounge or a bed or when inclosed in a cabinet. We attain these objects by the construction illustrated in the accompanying drawings, in which—

Figure 1 is a perspective view of a cabinet inclosing the bathing apparatus constructed in accordance with our invention. Fig. 2 is a rear perspective view of said cabinet, showing the bathing apparatus therein, but the folding legs of the bath-tub opened out. Fig. 3 is a perspective view of the folding legs of the bath-tub and the locking-board thereof detached to show their construction. Fig. 4 is a perspective view of the bathing apparatus in position for use; and Fig. 5 is a rear end view of the bathing apparatus with the tank, heater, and hose folded and the top of said tub closed and transformed into a lounge or bed.

In said drawings, A represents the frame of a cabinet of any suitable form. In the present instance it is provided with a writing-desk A², within which may be placed a wash-bowl, slop-jar, or other articles, and above said desk a mirror A³ forms one of the panels of the cabinet. The back of said cabinet, or one-half thereof, is left open, so that the bath-tub B can easily be introduced therein

and removed therefrom. Said tub is provided with casters b, so that it can easily be moved around a room.

To heat water that may be placed in the tub, the bathing apparatus is provided with a tank C, which is mounted on a metal plate D, supported on rods D², that extend down to a platform B², where they are bent parallel to said platform, and either secured thereto as shown in Fig. 4 or have the ends of said bent portion hinged to the end of the bath-tub adjacent to its bottom, as shown by dotted lines in said figure. In either case the platform B² is hinged to the bath-tub, and is intended to be paneled or to be otherwise of good appearance to inclose the bent lower ends of the rods D² and the hose H when said platform is turned upon its hinges b² against the end of the tub.

To heat the water in the tank C, the metal plate D of the stand is provided with a socket d, that receives the vertical tube E of a gasoline-burner E², that is retained at any desired distance under the tank, as the socket d is provided with a screw d², the end of which impinges against said tube E. The upper end of said tube carries the gasoline or oil reservoir e, the flow of which is regulated by the cock e² adjacent to the burner. The supporting-plate D is preferably centrally perforated to permit the flame of the burner to impinge directly against the bottom of the tank C.

If a comparatively small quantity of hot water is desired to mix with the water that may have been placed in the tub, said hot water may be drawn directly from the tank C through the cock e at the bottom thereof; but if a warmer bath is desired the water in the tub can be heated by conducting the steam produced in the tank C to said tub through the flexible hose H, that has its lower end attached to the waste or discharge opening b³ of the tub, and its upper end removably connected with the cover C² of the tank or with the upper portion of the latter.

If no water is first placed in the tub, the same tank and hose can be used to produce a steam or sweat bath by placing a blanket or

other suitable cover over the tub after the reception of the user, and allowing the steam from the tank to flow in the bottom of the tub. If a water-bath is used, the water there-
 5 in can be kept from flowing out even when the hose H is disconnected from the tank by having it rest upon the hook f, that is secured to the end of tub, near the top thereof, on a higher level than that reached generally by
 10 the water in said tub. When the water is to be discharged, the free end of the hose is removed from the hook f and directed into a drain or conductor leading outside of the house; but if there is no drain convenient the
 15 main portion of the water can be dipped out or drawn into pails. To facilitate the flow or emptying of the entire contents, the tub is provided with two pairs of legs L, hinged to the bottom thereof at l. The transverse con-
 20 necting-bar l² of each pair is united to the other by means of a horizontal rod l³, hinged to the connecting-bars l², so that the motion given to one pair of legs in opening or closing them will be simultaneously transmitted to
 25 the other. The legs are folded against the bottom of the tub when the latter is standing up, as shown in Fig. 2, by lifting the rod l³, (and with it the legs until they lie against said tub.) The rod is then in position to be locked or
 30 retained by means of a hook or a turn-button a³, secured to the top rail of the cabinet.
 When it is desired to have the legs opened out for use in supporting the tub in an ele-
 35 vated position, the rod l³ is released from the turn-button a³ and pulled out to the position shown in Fig. 2, and the legs are locked in that position by means of a board m, having one of its edges hinged at m² to the bottom of the tub, and its opposite edge is provided
 40 with a notch m³ to straddle the cross-bars l² of one of the pairs of legs. When the tub is thus elevated, the platform B² at the end thereof is supported by chain n, secured thereto and to said end of the tub.
 45 When the legs are folded, the tub can be used as a lounge by means of a padded cover P, placed thereon, and said cover can be pro-
 vided with a section P², hinged to its side and provided with legs p², to support the outer
 50 side of said section and transform it into a bed. When not used upon the tub, said cover

and section can be stored away in the recess A⁴, formed in the back of the cabinet.

It is evident that in place of the rubber hose H jointed pipes of other material may 55 be used to connect the tank to the tub. It is also evident that as the distance from the burner E² to the tank C can be regulated, and also the amount of burning-fluid led to the burner through the cock e², the production of 60 hot water or steam in the tank can be regulated to suit the bather. The bath-tub can be so handled, when it is to be used, that its heat-producing tank and burner can remain within the cabinet even while the water 65 therein is being heated.

Having now fully described our invention, we claim—

1. In combination with a cabinet having an open back and a turn-button or its described 7c equivalent, a bath-tub having legs hinged to the bottom thereof and a rod connecting them, substantially as described.

2. The combination of a bath-tub, a plat-
 form B², hinged to one end thereof, vertical 75 rods D², and a plate secured on top of said rods, and a tank upon said plate, substan-
 tially as and for the purpose described.

3. The combination of a bath-tub, a plat-
 form B², hinged to one end thereof, rods D², 80 secured to said hinged platform, a plate se-
 cured on top of said rods, a tank upon said plate, and a hose uniting said tank to the tub, substantially as described.

4. The combination of a bath-tub, a plat-
 form hinged to one end thereof, rods D², a 85 plate D, secured to said rods, a tube secured to said plate, and a burner on one end of said tube, substantially as described.

5. The combination of a bath-tub, a hose 90 attached to one end of said tub, a hook f, pro-
 jecting from said end to receive said hose, and a platform hinged to the end of the tub and adapted to inclose said hose and hook, 95 substantially as described.

In testimony whereof we affix our signatures in presence of two witnesses.

ISRAEL MARION SWANK.
 ALFRED C. COSNER.
